James Hamilton

UNITED STATES PATENT OFFICE.

JACOB JULIUS SCHEUCH, OF NEW YORK, N. Y., ASSIGNOR TO THE WHITE TAR COMPANY, OF NEW YORK, N. Y., A CORPORATION OF NEW YORK.

CLOSURE FOR MOTHPROOF BAGS.

1,130,342.

Specification of Letters Patent.

Patented Mar. 2, 1915.

Application filed December 17, 1910. Serial No. 597,756.

To all whom it may concern:

Be it known that I, JACOB JULIUS SCHEUCH, a citizen of the United States, residing in the borough of Manhattan, in the city, 5 county, and State of New York, have invented certain new and useful Improvements in Closures for Mothproof Bags, of which the following is a specification, reference being had to the accompanying drawings.

10 This invention relates to improvements in bags and particularly to improvements in bags commonly called "moth-proof" bags used as a receptacle in which to store furs, blankets, articles of clothing and the like in 15 order to keep them free from dust and moths.

An object of this invention is to provide a bag of the type just referred to which will be simple in construction, comparatively 20 cheap in manufacture and efficient and durable in use and in which the mouth of the bag will be securely closed against the entrance of dust, moths or the like.

In the drawings illustrating the principle 25 of this invention and the best mode now known to me of applying that principle, Figure 1 is a back view in elevation of my new bag; Fig. 2 is a front view of the bag in elevation, a part of the bag being broken 30 away to disclose the interior construction; Fig. 3 is a fragmentary view in perspective; Fig. 4 is a sectional detail on the line A—A of Fig. 1; and Fig. 5 is a fragmentary view showing the pivotal mounting of the clasps.

35 The bag *a* is formed with a rear or back wall *b*, a front wall *c* and lateral or side walls *d*, the latter being formed with folds *e*. The back wall *b* is provided with two plates *f*, *g*, the plate *f* being inside the bag 40 while the plate *g* is outside thereof. These plates *f*, *g* are fastened together, as by riveting, with the back wall interposed between them. The inside plate *f* is provided with hooks *f'* from which the articles may be suspended. The outside plate *g* is provided 45 with a bail *h* by which the bag *a* may be hung up on a peg or other suitable support. As is shown in Fig. 3 (which illustrates the bag open, while Figs. 1 and 2 show it 50 closed), the top of the front wall *c* extends above the mouth *i* of the bag, when the latter is open; and the upper edge of the front wall *c* is reinforced with a stiff binding-strip *c'*. When this strip is folded or dou- 55 bled over once, it covers the upper edge of

the back wall *b* and the mouth of the bag is thereby closed. Just below the stiff binding strip *c'* there is pivotally fastened to the front wall *c* at each side thereof a hook-shaped clasp *j*. As best shown in Fig. 4, 60 the mouth of the bag is closed by first folding the strip *c'* over the top edge of the back wall *b* and then making a second fold, whereby the top edge of the back wall is bent over and lies pressed against the front wall. The hook-shaped clasps *j* are then turned down from the dotted-line position of Fig. 1 to the full-line position thereof, wherein the ends of the strip *c'* and the folded parts of the walls of the bag are covered. Moreover, the strip *c'*, these folded parts and the walls on the opposite side of the strip therefrom are pressed firmly together. Thus, a very tight closure of the mouth of the bag is obtained. 70

I claim:

1. A bag of the character described having a front wall and a back wall, one of which walls projects above the other a distance sufficient to permit the projecting wall 80 to be folded over the other wall without folding the latter and which is provided with a pair of swinging clasps pivoted on the projecting wall below the line of the first fold and free to swing in a plane parallel to said walls and over the lateral edges of the bag; said clasps being adapted and arranged to lie in their closing position opposed to and over the lateral edges of the folded portions of said walls and to cover 85 and close the ends of the folded portions of the bag. 90

2. A bag of the character described having a front wall and a back wall, one of which walls projects above the other a distance sufficient to permit the projecting wall to be folded over the other wall without folding the latter and the upper edge of which is provided with a reinforcing strip; the wall having the projecting foldable 100 portion being provided with a pair of swinging clasps pivoted below the reinforcing strip and free to swing in a plane parallel to said walls and over the lateral edges of the bag; said clasps being adapted and arranged to lie in their closing position opposed to and over the lateral edges of the folded portions of said walls and to cover 105 and close the ends of the folded portions of the bag. 110

- 2
3. A bag of the character described having a front wall and a back wall and open at only its mouth; one of which walls projects above the other a distance sufficient to permit the projecting wall to be folded over the other wall without folding the latter and which is provided with a pair of swinging clasps pivoted on the projecting wall and free to swing in a plane parallel thereto and arranged and adapted to fit in their closing position over and to cover and close the ends of the folded portions of the bag only after said projecting wall has been twice folded upon itself.
- 10 4. A bag of the character described having a front wall and a back wall and open at only its mouth; one of which walls projects above the other a distance sufficient to permit the projecting wall to be folded over the

other wall without folding the latter and 20 which is provided with a pair of swinging hook-shaped clasps pivoted on the projecting wall and free to swing in a plane parallel thereto; the hook ends of said clasps being arranged to swing over the lateral edges 25 of the bag and to embrace and close the ends of the folded portions of the bag only after the projecting wall has been twice folded upon itself.

In testimony whereof I hereunto set my 30 hand this sixth day of November, 1910, at New York city, N. Y., in the presence of the two undersigned witnesses.

JACOB JULIUS SCHEUCH.
